UNITED STATES PATENT OFFICE

ERNST F. W. ALEXANDERSON, OF SCHENECTADY, NEW YORK, ASSIGNEE TO GENERAL ELECTRIC COMPANY, A CORPORATION OF NEW YORK

ELECTRIC-DISCHARGE DEVICE

Application filed November 16, 1927. Serial No. 233,722.

The present invention relates to electric discharge devices. In three-element electric discharge devices, it is common to employ a high tension direct current supply for the plate or anode circuit and a low tension direct current supply for the filament. It is often desirable, however, to employ a single source of potential for these elements and it is one of the objects of the present invention

10 to provide an improved electric discharge device in which a single source of high potential direct current may be employed to heat the filament and at the same time supply the necessary voltage to the plate circuit.

15 The novel features which I believe to be characteristic of my invention are set forth with particularity in the appended claims. My invention itself, however, will best be understood from reference to the following specification when considered in connection with the accompanying drawing, in which Figs. 1 and 2 respectively show diagrammatically a three-electrode electron discharge device and a two-electrode electron discharge

20 device embodying the features of the present invention.

25 Referring to the drawing, I have indicated at 1 a container adapted to be maintained at a vacuum or low gas pressure as desired.

30 A plurality of electrodes comprising an anode 2, grid 3 and cathode 4 are mounted in the container. The cathode comprises a hollow cylindrical metal member coated on the outside with a suitable oxide so that it will emit electrons at a relatively low temperature.

35 The cathode is adapted to be heated from the inside and for this purpose a tungsten or other suitable heating element or wire 5 is placed within the cathode and connected in circuit with a thermostatic strip 6 and a contactor 7, the contactor and thermostatic strip being separated by a block of insulating material 8. The lower end of the strip 6 is rigidly mounted in container 1, the

40 upper end being free to move to the left of the position shown in Fig. 1 when the strip is heated to a certain temperature and to thereby separate contactor 7 and cathode 4.

45 In operation, a source of high voltage direct current 10 is connected to anode 2 and

cathode 4, the thermostatic strip 6 being connected to the anode through a resistor 11. When the discharge device is cold and a power switch, not shown, closed, a circuit is completed from the source of current 10 through resistor 11, heating resistor 5 and cathode 4 to the other side of the current source 10. Current flows in this circuit, heating cathode 4 and the thermostatic strip 6. When the cathode becomes heated to such an extent that strip 6 bends toward the left of the position shown in Fig. 1 the strip 6 breaks the electrical contact between contactor 7 and cathode 4. The heating element 5 then assumes a positive potential with reference to the cathode 4 and is therefore subject to bombardment by electrons which maintain it at white heat.

50 If desired, the discharge device may be employed to produce high frequency oscillations for the excitation of a vapor lamp 9. This may be done by connecting the ends of a transformer winding 12 to the plate and grid members of the tube 1, the central point of the transformer winding being connected to the cathode. A secondary transformer winding 13, in inductive relation to winding 12, is connected to a coil 14 surrounding vapor lamp 9. While I have illustrated the discharge device as furnishing a source of high frequency current to lamp 9, it obviously is not limited to this particular use.

55 The invention may be readily adapted for use as a rectifier as disclosed in Fig. 2. In this figure, like reference characters are employed to indicate similar parts appearing in Fig. 1. In Fig. 2 an anode 2, cathode 4, heater element 5 and thermostatic strip 6 are mounted in a receptacle 1. A resistance element 11 is connected as in Fig. 1 between the anode and heater element while the cathode and anode are connected to the secondary winding 15 of a transformer 16 and to a condenser 17.

60 Alternating current is supplied to the primary winding 18 of transformer 16 from mains 19. If the discharge device is cold and the power switch (not shown) open, contactor 7 will engage the cathode 4 so that when the power switch is closed, heating current will

flow through resistor 11, heater 5, cathode 4 and condenser 17. When the cathode is heated to a certain temperature, direct current flows through the tube and in the output circuit 20. The thermostatic strip 6 breaks the 5 contact between the cathode and contactor 7 at a certain temperature, but the temperature will be maintained by the electron discharge between the cathode and the heating element.

What I claim as new and desire to secure by 10 Letters Patent of the United States is:—

1. An electron discharge device comprising a receptacle, an anode and cathode mounted in the receptacle, the cathode including a heater element, said heater element being 15 mounted in the receptacle and electrically connected with the cathode, and current responsive means for breaking the contact between the heater element and cathode.

2. An electron discharge device comprising 20 a receptacle, an anode and cathode mounted in the receptacle, the cathode including an inner heater element, said heater element being mounted in the receptacle and electrically connected with the cathode, and temperature responsive means for breaking the contact between the inner heater element and cathode.

3. An electron discharge device comprising 25 a cathode and anode, said cathode comprising a hollow cylindrical member, a heater element mounted in said cylindrical member and electrically connected with said member, and means for breaking the electrical contact between the heater element and cylindrical member.

4. An electron discharge device comprising 30 a receptacle, an anode and cathode mounted in the receptacle, the cathode including a heater element, said heater element being mounted in the receptacle and electrically connected with the cathode, current responsive means for breaking the connection between the heater element and cathode and means for producing a discharge across the 45 broken connection whereby the cathode continues to be heated.

5. An electron discharge device comprising 50 a receptacle, an anode and cathode mounted in the receptacle, the cathode including an inner heater element, said heater element being mounted in the receptacle and electrically connected with the cathode, temperature responsive means for breaking the connection between the inner heater element and cathode 55 and means for causing a flow of current between the cathode and heater members whereby the temperature of the latter is maintained.

6. An electron discharge device comprising 60 a cathode and anode, said cathode comprising a hollow cylindrical member, a heater element mounted in said cylindrical member and electrically connected with said member, means for breaking the electrical connection between the heater element and cylindrical 65 member and means for producing a bombard-

ing discharge between the cathode and heater members whereby each of the latter is maintained at an operating temperature.

In witness whereof, I have hereunto set my hand this 14th day of November, 1927.

ERNST F. W. ALEXANDERSON.
